UNITED STATES PATENT OFFICE.

JULIAN CARRILLO, OF NEW YORK, N. Y.

SNOW-MELTER.

1,215,620.

Specification of Letters Patent. Patented Feb. 13, 1917.

Application filed May 20, 1915. Serial No. 29,442.

To all whom it may concern:

Be it known that I, JULIAN CARRILLO, a citizen of the Republic of Mexico, residing at New York, in the county of New York and State of New York, have invented certain new and useful Improvements in Snow-Melters; and I do hereby declare the following to be a full, clear, and exact description of the invention, such as will enable others skilled in the art to which it appertains to make and use the same.

The present invention relates to an improved means for disposing of snow and ice on streets and roads, and the principal object of the invention is the provision of a convenient and easily operated means to this end whereby the snow and ice deposit may be rapidly melted where it falls and carried off through the sewers or other avenues provided for the purpose of disposing of surface water. By employment of my invention the labor and congestion of streets and docks, incident to transporting of snow and ice in cities, is entirely avoided.

In its broadest aspect, the invention is capable of embodiment in various forms, some of which are illustrated in the accompanying drawings wherein Figure 1 is a side elevation of one complete snow melter, certain parts being removed for the sake of clearness, Fig. 2 is a transverse section of the same on the line 2—2 in Fig. 1, Fig. 3 is a diagrammatic view of the heating plate seen from above in connection with the plate-hoisting means, Fig. 4 is a detail view, and Fig. 5 is a side view of a modified form.

My invention involves the use of a wagon, a melting plate adapted to be heated and supported beneath the wagon by means capable of raising and lowering said plate, and heating means for the plate preferably supplied from devices carried by the wagon.

In the form shown in Fig. 1 I employ an automobile frame 10, on wheels 11, and driven in any desired manner, as by a motor 12. The driver's seat is at 13, and the steering wheel at 14.

Under the frame 10 is a long heating plate 15 preferably occupying all the available space between the wheels 11. This plate is normally suspended by cords or cables 16 wound upon drums 17, and means are supplied for rotating all the drums simultaneously to roll up the cables and lift the

plate 15 when desired. The power for this purpose may come from any desired source, and preferably from the same motor that drives the automobile frame 10.

In Figs. 1, 2 and 3 a preferred means for this purpose is shown. This comprises a shaft 18 for each drum, all said shafts being driven by bevel gears 19 from a common shaft 20. On an extension 21 of the driving shaft of the motor 12 is a pinion 22 which drives a gear wheel 23 normally loose on the shaft 20. By means of a clutch 24, controlled by a handle 25, the gear 23 may be made to rotate the shaft 20 in a well known manner.

When the plate 15 is fully raised, as shown in dotted lines in Fig. 1, it is prevented from dropping again by a ratchet wheel 26 and pawl 27, which is releasable at will by a pedal 28.

In this particular embodiment of my invention the heating means for the plate 15 comprise gas burners 29 within the plate supplied by flexible pipes 30 from a gas tank 31 on the frame 10. The plate is preferably perforated as shown to admit air to the burners. It is also preferable in this form to utilize the plate 15 as a muffler, carrying the exhaust from the motor 12 into said plate, as by the protected tubing 32. Economy of fuel is thereby effected, and the melting operation is accelerated.

In operation, the car having been brought to the portion of the street where the melting is to be begun, the motor is disconnected from the driving wheels in a well known manner by the lever 33, and the ratchet 26 is liberated by pressing the pedal 28, allowing the heated plate to drop down upon the snow surface.

When the snow beneath the plate has been melted in this way, the clutch 24 is employed to connect the still running motor with the hoisting drums 17, to lift the plate. The clutch is then disconnected and the car moved to a new snow surface where the above operation is repeated.

In the form shown in Fig. 5, the plate 15 is electrically heated by the coils 34 within it. These coils are connected by suitable wires 35 with the generator 36 on the frame 10, and this generator is driven from the motor shaft 21, through gears 37, 38, and a clutch 39 controlled by a handle 40, so that the generator may be stopped and started.

independently of the motor 12. The operation of this modification of my invention is obvious.

My invention, as above described, makes it possible to dispose of snow rapidly and effectually with greatly reduced labor and without the congestion of traffic at present experienced in city work of this kind.

Various changes may be made in my apparatus without departing from the scope of my invention, and I do not limit myself to the details herein shown and described.

What I claim is—

- 15 1. A snow melting apparatus comprising a vehicle, a substantially horizontal heat-conducting plate supported beneath the same and adapted to be laid in direct contact with the snow surface, heating means for said plate supported over the same and 20 adapted to move with it and means on the vehicle adapted to lower the plate against the snow surface and to lift it away from the same at will.
- 25 2. A device of the class described comprising a vehicle, a heating plate beneath the same, a motor adapted to move the vehicle, a hoisting device for said plate on the vehicle, heating means on said plate and vehicle, and means for connecting said motor at will to operate said hoisting device.
- 30 3. A device of the class described comprising a vehicle, a heating plate beneath the same, a motor adapted to move the vehicle,

hoisting drums on the vehicle, cables from said drums to said plate, means on the plate and vehicle for heating the plate, means for connecting said motor to said drums at will, and means for preventing unwinding of the drums when the plate is lifted.

4. A snow melting apparatus comprising a vehicle, a substantially horizontal metal plate supported movably beneath the same, electric heating coils for said plate supported immediately over the same and adapted to move with it, means on the vehicle for hoisting and lowering said plate and electric heater, an electric generator on the vehicle, and flexible electric connections between said generator and said coils above the heating plate.

5. A snow melting apparatus comprising a substantially horizontal heat-conducting plate adapted to be lowered into contact with the snow surface, heating means for said plate supported above the same, and means for raising and lowering said plate so as to bring it at will either into or out of contact with said snow surface.

In testimony whereof, I affix my signature, in presence of two witnesses.

JULIAN CARRILLO.
